US00D865671S

(12) **United States Design Patent** (10) **Patent No.:** **US D865,671 S**
(45) **Date of Patent:** **** Nov. 5, 2019**

(54) **ELECTRIC POWER DISTRIBUTION UNIT**

(71) Applicant: **Delta Electronics (Thailand) Public Company Limited**, Samutprakarn (TH)

(72) Inventors: **Kai Dong**, Samutprakarn (TH); **Keting Fang**, Samutprakarn (TH); **Hongming Li**, Samutprakarn (TH); **Jie Ruan**, Samutprakarn (TH); **Zhongwei Ke**, Samutprakarn (TH)

(73) Assignee: **DELTA ELECTRONICS (THAILAND) PUBLIC COMPANY LIMITED**, Samutprakarn (TH)

(**) Term: **15 Years**

(21) Appl. No.: **29/659,471**

(22) Filed: **Aug. 9, 2018**

CLAIM

The ornamental design for an electric power distribution unit, as shown and described.

DESCRIPTION

FIG. 1 is a perspective view of an electric power distribution unit showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings are for the purpose of illustrating portions of the electric power distribution unit that forms no part of the claimed design.

1 Claim, 4 Drawing Sheets
